UNITED STATES PATENT OFFICE.

SAMUEL A. JONES, OF DESHLER, OHIO.

DESIGN FOR A ROOFING-TILE.

No. 39,274.

Specification for Design.

Patented April 21, 1908.

Application filed January 7, 1907. Serial No. 351,272. Term of patent 14 years.

To all whom it may concern:

Be it known that I, SAMUEL A. JONES, a citizen of the United States, residing at Deshler, in the county of Henry and State of Ohio, have invented a new, original, and ornamental Design of Roofing-Tile, of which the following is a specification, reference being had to the accompanying drawings, forming part thereof.

In the drawing: Figure 1 is a perspective view showing the front face of the tile. Fig. 2 is a bottom plan view of the tile.

I claim

The ornamental design for a roofing tile, as shown.

SAMUEL A. JONES.

Witnesses:

LESTER BLAKE,
F. M. ARMSTRONG.
